UNITED STATES PATENT OFFICE

2,364,910

DRESSINGS STERILIZER

George H. Myrick, Rochester, Minn.

Application October 25, 1939, Serial No. 301,110

9 Claims. (Cl. 68—21)

My invention relates to improvements in dressings sterilizers of the general type in which hot, damp surgical dressings are prepared for use as fomentations.

It is the principal object of the present invention to provide a novel dressings sterilizer that effectively sterilizes and dampens surgical dressings and enables excess moisture to be easily and safely removed therefrom, without danger of contaminating the dressings.

A more specific object of the present invention is to provide an improved substantially closed sterilizer which accomplishes boiling or steaming of the dressings, together with the removal of excess moisture therefrom, before the sterilizer is opened for their removal.

A further object is to provide a novel sterilizer which accomplishes the above and enables squeezing of excess moisture from the dressings without necessitating removal of the hot water from the sterilizer.

An additional object is to provide a sterilizer with effective means for accomplishing the foregoing objects, without recourse to elements of construction that might contaminate the dressings by allowing moisture condensed outside the sterilizer to drip upon the dressings or into the interior of the sterilizer.

It is a further object to provide a sterilizer having the advantages indicated above that, in addition, has provision for sterilizing a pair of dressings handling forceps along with the dressings.

Other objects and advantages of my invention will become apparent from the ensuing description, in the course of which reference is had to the following drawings in which:

Fig. 1 is a plan view of a sterilizer embodying the present invention with a portion of the balls broken away in the interest of clarity of illustration;

Fig. 2 is a front elevation of the sterilizer illustrated in plan in Fig. 1;

Fig. 3 is a horizontal sectional view which may be considered as taken in the direction of the arrows substantially along the line 3—3 of Fig. 5, with a portion of the cover broken away to show the structure therebeneath;

Figs. 4 and 5 are similar vertical sectional views taken in the direction of the arrows along the lines 4—4 and 5—5 of Fig. 3. In these views, Fig. 4 illustrates the parts in the positions they assume when the dressings are being sterilized, while Fig. 5 shows the same parts in the posi-

tion assumed when squeezing excess moisture from the dressings;

Figs. 6 and 7 are vertical sectional views similar to Figs. 4 and 5, respectively, but taken in the direction of the arrows along the lines 6—6 and 7—7 of Fig. 3; and

Fig. 8 is a vertical sectional view through one of the stub shafts and associated parts and may be considered as taken in the direction of the arrows along the line 8—8 of Fig. 2.

In the following description, like reference characters refer to like parts throughout the several views.

In general, the embodiment of my invention illustrated in the drawings comprises a base 10 of truncated pyramidal form, containing a downwardly opening recess 12 having an electrical heating unit 14 therein. This heating unit is connected at one side of the base to an electrical plug 16 and cord 18, through which the heating unit is energized. After installation of the heating unit 14 within the recess 12, the recess 12 is closed by a rectangular base plate, not shown, secured in place by four screws, which extend into the base through apertures in the corners of the base plate. These screws also serve as feet to support the sterilizer and are, therefore, provided with large heads 20, preferably composed of a plastic substance such as hard rubber, Bakelite, or the like.

A rectangular tank 22 surmounts the base 10 and is preferably formed as a unitary casting therewith.

A cover 24 is attached at one edge to the top 35 of the tank by hinges 26, which permit opening and closing of the receptacle formed by the side walls 28 and bottom 30 of the tank 22. A stop member 32 secured to the cover adjacent the hinges 26 abuts against the rear wall of the tank 40 when the cover is raised and tilted backwardly somewhat beyond the vertical. This stop member 32 serves to support the cover in opened position until it is desired that it be closed. The edge of the cover opposite the hinge 26 has 45 the upper end of a depending bayonet latching member 34 pivoted thereto. This latching member 34 cooperates in a well-known manner with a pin 36 extending from the front wall of the tank 22 to secure the cover 24 in closed position.

Inside the tank 22, the front and back walls are each provided with a vertical grooved track 38, which extends approximately two-thirds of the distance from the top edge of the tank toward the bottom thereof. These tracks serve 55 to guide the vertical movements of a rectangular

perforated basket 40 which fits within the tank and serves to contain the dressings to be treated. This basket is provided on its front and rear walls with a pair of vertically spaced pins 42, which extend into the grooved tracks 38. These pins, in conjunction with the tracks, prevent lateral or tilting movements of the basket, but permit free vertical movement thereof, except that the lower ends 44 of the tracks 38 limit the downward movement of the basket to a position about one and one-half inches from the bottom of the tank.

Two bails 46 serve as handles to carry the sterilizer and also have the more important function of providing a means for extracting excess moisture from the steamed dressings. These bails have their ends 48 connected to horizontal stub shafts 50 which are journaled through bosses 52, cast integrally with the front and back walls, and extend into the interior of the tank. As best illustrated in Fig. 8, the outward ends of the stub shafts 50 are squared, as at 54, and fit into complementary squared openings in the ends 48 of the bails 46. Thus, when the bails 46 are moved apart and pressed downwardly, the stub shafts will be rotated through approximately a quarter of a revolution.

The inner ends of these stub shafts 50 are secured to leaf cams or levers 56, which project downwardly when the bails are together, but which, when the bails are moved apart and pressed downwardly, are rotated into contact with the lower of the pins 42 and lift the basket upwardly. Stops 58, projecting inwardly from the front and back walls of the tank, are engaged by the cams or levers 56 when the basket 40 is raised to a position such that its top edge is flush with the top of the tank. These stops are provided to prevent too energetic movement of the bails from lifting the basket completely out of the tank.

The inside surface of the cover 24 carries a rectangular presser plate 60 spaced therefrom by an X member 62. This presser plate 60 is approximately parallel to the cover 24 and is spaced downwardly a distance somewhat less than the depth of the basket 40. In the embodiment shown, it is intended that the cover 24, X member 62 and presser plate 60 be cast as a single unitary part.

In operation, a quantity of water which may be medicated or not, as desired, is poured into the tank. The basket is then inserted into the tank with its pins 42 extending into the tracks 38. The dressings to be treated are placed within the basket and the basket lowered by raising the bails somewhat. After the cover 24 is closed and the bayonet catch 34 is secured, the heating element is energized through the cord 18 to boil the water in the tank and thus treat and sterilize the dressings.

After the elapse of a sufficient treating period, the bails are pulled apart and pushed downwardly. This operation raises the basket, as previously described, and squeezes the dressings between the bottom of the basket and the presser plate 60. Excess moisture is thereby pressed from the dressings and flows back into the tank through the perforations in the basket 40. The bayonet catch may then be unlatched, the cover swung back, and the dressings removed and applied to the patient.

For the purpose of lifting the dressings from the sterilizer, I prefer to use a pair of forceps, not shown, which are intended to extend into the sterilizer along the side of the basket 40 through

a cutaway corner 64 of the cover 24. The lower portions of the forceps, being in the sterilizer, are thus sterilized simultaneously with the dressings. This expedient conveniently insures the dressings applied to the patient arriving in sterile condition.

With my sterilizer, as described above, it is optional with the user whether enough water is placed in the tank to immerse the dressings being sterilized, or whether less water is used and the dressings treated only with steam from the boiling water. In either case, perfect sterilization is effected and excess moisture removed from the dressings in the manner previously described.

Since the stub shafts 50 are above the water level, no packing is necessary to prevent leaking. It should also be noted that since these shafts are horizontal, steam will not condense upon them outside the sterilizer and then run back into the sterilizer to contaminate the dressings in the manner that might result were an arrangement used in which vertical shafts were passed through openings in the cover.

When cleaning of the sterilizer becomes desirable, it will be seen that the cover may be swung back and the basket lifted out of the tank to give free access to the interior thereof.

Although, in the interest of brevity, no detailed description of the heating unit 14 has been given, it will be appreciated that this heating unit may be constructed in any suitable well-known manner and is preferably provided with a control means to open the heater circuit, if the water level in the sterilizer becomes low enough to endanger overheating. One suitable heating unit adaptable for use with this sterilizer is fully described in my Patent No. 2,184,679, granted December 26, 1939.

Having illustrated and described a preferred embodiment of my invention, what I claim as new and useful and desire to secure by Letters Patent of the United States is:

1. A sterilizer of the class described comprising a tank adapted to contain liquids therein, a cover for said tank, a basket movably supported in said tank for reciprocation vertically therein independently of and relative to the cover, a presser plate positioned below said cover and secured thereto, said plate being of a size to enter said basket, lifting means movably secured to said tank for lifting said basket to squeeze the contents therein against said presser plate when said cover is closed, and manually operable means outside of said tank to actuate said lifting means, said last mentioned means constituting bails for carrying the tank.

2. A sterilizer of the class described comprising a tank adapted to contain liquids therein, a cover for said tank hinged along one edge thereof and provided with latching means to hold said cover closed, a basket movably supported in said tank for reciprocation vertically therein independently of and relative to said cover, guide means supported by said tank coacting with said basket for maintaining the latter horizontal during vertical movements thereof, a presser plate of a size to enter the basket and positioned below said cover a distance substantially equal to the depth of said basket, said presser plate being fixed rigid with said cover, lifting means movably secured to the tank for lifting said basket to squeeze the contents therein against said presser plate when said cover is latched closed, and manually operable means outside of said tank to actuate said lifting means.

3. A sterilizer of the class described comprising a tank adapted to contain liquids therein, a cover for said tank hinged along one edge thereof and provided with latching means to hold said cover closed, a basket movably supported in said tank for reciprocation vertically therein independently of and relative to said cover, guide means in said tank coacting with said basket to guide the vertical movement thereof, a presser plate of a size to enter the basket and positioned below said cover a distance substantially equal to the depth of said basket, said presser plate being fixed rigid with said cover, lifting means movably secured to the tank for lifting said basket to squeeze the contents therein against said presser plate when said cover is latched closed, manually operable means outside of said tank to actuate said lifting means, and stop means to prevent the lifting means from raising the top edge of said basket substantially above the top edge of said tank.

4. A dressings sterilizer comprising: an open top tank adapted to contain liquids therein, a basket positioned within said tank, vertical guide ways in said tank to guide said basket for vertical reciprocation, lifting mechanism in said tank to lift said basket, manually operable means outside said tank to actuate said lifting mechanism, a horizontal shaft extending through a side wall of said tank above the liquid level therein and connecting said manually operable means to said lifting mechanism, a cover to close the open top of said tank, and a presser plate of a size to enter the basket positioned below said cover and secured thereto, whereby hot soaked dressings in said basket may be raised above the liquid in said tank and pressed against the presser plate to remove excess moisture from said dressings without raising said cover or endangering contamination of said dressings by allowing moisture condensed outside said tank to flow back thereinto.

5. A sterilizer of the class described comprising a tank adapted to contain liquids therein, a cover for said tank, a basket positioned in said tank and having guiding members projecting from two opposite side walls thereof, vertical tracks on the inside of said tank co-operating with said guide members, a presser plate of a size to enter the basket positioned within said tank and above said basket, mechanism adapted to lift said basket to squeeze the contents therein against said presser plate, said mechanism comprising a pair of bails for carrying said sterilizer, horizontal stub shafts journaled in the side walls of said tank above the liquid level therein and having their outward ends connected to said bails, and cams connected to the inner ends of said stub shafts and adapted when rotated to contact said guide members and lift said basket, whereby said basket is lifted and excess moisture squeezed from said dressings when said bails are pulled apart and pressed downwardly.

6. A sterilizer of the class described comprising a tank adapted to contain liquids therein, a cover for said tank, a basket movably supported in said tank for reciprocation vertically therein

independently of and relative to the cover, a presser plate of a size to enter the basket and located within said tank in a position above said basket when said cover is closed, lifting means movably secured to said tank for lifting said basket to squeeze the contents therein against said presser plate when said cover is closed, means in said tank associated with said lifting means to limit movement of the basket to a point near the top of the tank, and manually operable means outside of said tank to actuate said lifting means.

7. A sterilizer of the class described comprising a tank adapted to contain liquids therein, a cover for said tank, a support for materials to be sterilized positioned in said tank and adapted to reciprocate vertically therein, said material support being of a size to leave a space therebetween and the tank, a presser plate of a size to leave a space therebetween and a tank in alignment with the first mentioned space and adapted to be located within said tank in a position above said material support, lifting means adapted to lift said material support to squeeze the dressings thereon against said presser plate, manually operable means outside of said tank to actuate said lifting means, and an opening in said cover over said space between the tank and material support through which a pair of dressings handling forceps can extend to be sterilized simultaneously with said dressings.

8. A sterilizer of the class described comprising a tank adapted to contain liquids therein, a cover for said tank, a support for material to be sterilized positioned in said tank and adapted to reciprocate vertically therein, a presser plate adapted to be located within said tank in a position above said material support, mechanism adapted to lift said material support to squeeze the contents therein against said presser plate, said mechanism comprising a pair of bails for carrying said sterilizer, horizontal stub shafts journaled in the side walls of said tank above the liquid level therein and having their outward ends connected to said bails, cams connected to the inner ends of said stub shafts and adapted when rotated to lift said material support, whereby the latter is lifted and excess moisture squeezed from the material when said bails are pulled apart and pressed downwardly.

9. A sterilizer of the class described comprising a tank adapted to contain liquids therein, a cover for said tank, a basket movably supported in said tank for reciprocation vertically therein independently of and relative to the cover, a presser plate of a size to enter the basket and located within said tank in a position above said basket when said cover is closed, lifting means movably secured to said tank for lifting said basket to squeeze the contents therein against said presser plate when said cover is closed, manually operable means outside of said tank to actuate said lifting means, and stop means associated with said lifting means to limit the movement of the basket to prevent the basket from being raised above the top edge of said tank.

GEORGE H. MYRICK.
